US00D806521S

(12) **United States Design Patent** (10) Patent No.: **US D806,521 S**
(45) Date of Patent: ** Jan. 2, 2018

(54) **MOUNT FOR ELECTRONIC DEVICES**

(71) Applicant: **Innovenis, Inc.**, Sammamish, WA (US)

(72) Inventor: **Eric John Wengreen**, Sammamish, WA (US)

(73) Assignee: **Innovenis, Inc.**, Sammamish, WA (US)

(**) Term: **15 Years**

(21) Appl. No.: **29/593,756**

(22) Filed: **Feb. 13, 2017**

Related U.S. Application Data

(63) Continuation of application No. 15/424,837, filed on Feb. 4, 2017.

(51) **LOC (11) Cl.** **08-05**

(52) **U.S. Cl.**

USPC **D8/354**

(57) **CLAIM**

The ornamental design for a mount for electronic devices, as shown and described.

DESCRIPTION

FIG. 1 is a front, first side, and top perspective view of a mount for electronic devices embodying the new design; FIG. 2 is a back, second side, and bottom perspective view thereof;

FIG. 3 is a back view thereof;

FIG. 4 is a front view thereof;

FIG. 5 is a second side view thereof;

FIG. 6 is a first side view thereof;

FIG. 7 is a bottom view thereof; and,

FIG. 8 is a top view thereof.

The uniform repeating broken lines depict portions of a mount for electronic devices in which the claimed design is embodied and form no part of the claimed design.

1 Claim, 6 Drawing Sheets
